UNITED STATES PATENT OFFICE.

MARSHALL C. LEFFERTS, OF NEW YORK, N. Y., ASSIGNOR TO THE CELLULOID COMPANY, OF SAME PLACE, A CORPORATION OF NEW JERSEY.

DESIGN FOR A RAZOR-HANDLE, &c.

SPECIFICATION forming part of Design No. 30,588, dated April 18, 1899.

Application filed March 10, 1899. Serial No. 708,613. Term of patent 7 years.

To all whom it may concern:

Be it known that I, MARSHALL C. LEFFERTS, a citizen of the United States, residing in the city, county, and State of New York, have invented and produced a new and original Design for Razor-Handles and the Like, of which the following is a specification.

My invention relates to designs for razor-handles and the like; and it consists in the article provided with the surface ornamentation, substantially as herein shown and described.

In the drawings forming part of this specification, Figure 1 is a side elevation, and Fig. 2 an end elevation, of a razor-handle ornamented by my design.

The handle of conventional form is ornamented on the exterior of its two parts 1 2, as follows: At 3 are transverse ranges of leaves overlapping each other for a portion of their

lengths and covering the exterior surface of the parts 1 2, the disposition of the central veins of the leaves following substantially the direction of the outline of the parts 1 2. At 4 5 6 are crossed bands extending across the exterior of the parts 1 2 and located adjacent and intermediate the ends of said parts.

All the ornamental figures are in relief, and the crossed bars are raised above the leaves, which form a background therefor.

Having described my invention, I claim—

The design for a razor-handle, or similar article, substantially as herein described and shown.

Signed at the city, county, and State of New York this 9th day of March, 1899.

MARSHALL C. LEFFERTS.
